UNITED STATES PATENT OFFICE

GUSTAV E. MEISSNER, OF NEW YORK, N. Y.

DESIGN FOR A TEAPOT

Application filed January 19, 1931. Serial No. 38,381. Term of patent 3½ years.

To all whom it may concern:

Be it known that I, GUSTAV E. MEISSNER, a citizen of the United States, residing at New York, in the county and State of New York, have invented a new, original, and ornamental Design for a Teapot, of which the following is a specification, reference being had to the accompanying drawing, forming a part thereof, in which the figure is a front perspective view of the article, showing my new design, the lid being open.

I claim:

The ornamental design for a teapot, as shown.

In testimony whereof I affix my signature.

GUSTAV E. MEISSNER.
